BOOK

Milton H. Harris, Brooklyn, N. Y.

Application November 30, 1940, Serial No. 367,869

4 Claims. (Cl. 281—16)

This invention relates generally to books, and particularly to bound volumes that have a permanent body of leaves bound between covers and are adapted to receive a removably attachable supplement.

Such supplements are used to bring previously published volumes up to date. For example, permanently bound law books containing annotated statutory codes or digests of judicial decisions are subject to constant legislative amendment or judicial interpretation. Law publishers meet this condition by periodically printing supplements whose contents are arranged and intended for interpolation into the earlier permanent volumes.

It is obvious that these permanent volumes and their supplements, being related by a common subject matter, also should be physically associated. Not so apparent, but equally important, the physical connection must be such that it neither interferes with a contemporaneous search of the pages of both the permanent volume and its companion supplement, nor prevents a visual correlation of related sections from each.

Existing removable supplement books are constructed so that the leaves of the permanent volume and the leaves of its attached supplement turn in substantially the same orbit. Consequently, when the permanent volume is open, it is impossible to turn the leaves of its attached supplement, and vice-versa. For the same reason, it is impossible to have the leaves of both the permanent volume and its attached supplement fully open concurrently for joint examination. These difficulties can be overcome only by removing the supplement from its pocket. Such removal, however, defeats a prime object of an attachable supplement: the physical association of permanent volume and supplement so that the latter will not be lost or mislaid or the wrong supplement consulted.

The object of this invention, therefore, is to provide a book with a removable supplement wherein the leaves of the permanent volume can be turned without interfering with the open leaves of its attached supplement, and vice-versa. A co-ordinate object of the invention is the provision of a book of this type wherein the permanent volume and its attached supplement concurrently can be fully open for joint examination. Other objects and a fuller understanding of my invention may be had by referring to the following description and claims, taken in conjunction with the accompanying drawing in which:

Fig. 1 is a perspective view of the permanent volume with its rear cover open, showing the

empty cover pocket by means of which the supplement is attached to the permanent volume.

Fig. 2 is a plan view of the supplement's coupling member to which the supplement leaves are secured.

Fig. 3 is a perspective view of the coupling member with the supplement leaves secured thereto, one of its arms being folded for insertion into the cover pocket.

10 Fig. 4 is a perspective view of the supplement inserted in its cover pocket, the supplement leaves being extended for use.

15 Referring to the parts by numerals, 1 and 2 respectively designate the front and rear covers of the permanent volume and 3 its back. The back 3 of the permanent volume is made wider than the thickness of its body of leaves 4 in order to provide a space between the leaves 4 and the rear cover 2 to receive a removable supplement, the difference in width being substantially equal to the thickness of the supplement to be accommodated. The leaves 4 are permanently bound to the back 3, their bound edges being distributed along the back 3 from cover 1 to cover 2 in order to lend support to the back 3.

20 The rear cover 2 has a layer of material 5 secured thereto at its forward and side edges. This layer extends rearwardly to a point adjacent the back 3 and forms with the inner face of the rear cover 2 a pocket 6 which opens vertically adjacent the back 3.

25 The supplement is formed of a coupling member and a plurality of leaves 7.

30 The coupling member is made of flexible material which is stiffer than the leaves 7. As shown in Fig. 2, it is of irregular shape, having one arm, hereinafter called the tapered arm 8, of a size and shape allowing a snug but temporary insertion into the pocket 6, and having a 35 second arm which serves as a back cover member for the supplement leaves, and which is hereinafter called the cover arm 9. The cover arm 9 is slightly smaller in length and width than the rear cover 2 of the permanent volume.

40 It will be noted that the tapered arm 8 and the cover arm 9 project from a trunk 10 of the coupling member of the supplement. The tapered arm 8 is folded backwards under the trunk 10, the fold being made along the vertical line 11 which is common to that arm 8 and the trunk 10. The cover arm 9 is folded forward and above the trunk 10, the fold being made along the horizontal line 12 which is common to that arm 9 and the trunk 10. The creases along these 45 lines 11, 12 of fold may be reinforced with tape.

The leaves 7 of the supplement are slightly shorter and narrower than the cover arm 9. These leaves 7 are secured thereto by staples 13 so that their bottom edges are slightly higher than the horizontal line of fold 12 in the coupling member.

The supplement is attached to the book by inserting the tapered arm 8 into the cover pocket 6, as shown in Fig. 4. The insertion should be made so that the horizontal line of fold 12 in the coupling member is slightly below the top of the rear cover 2 of the permanent volume. The snug fit of the arm 8 in the pocket 6 will maintain this juxtaposition.

Because absolute dimensions are not a part of this invention, relative terms have been employed in describing the size of the supplement leaves 7, the tapered arm 8, and the cover arm 9; likewise in describing the juxtaposition of the supplement leaves 7 and cover arm 9 and the juxtaposition of the cover arm 9 and the rear cover 2 of the permanent volume. Functionally speaking, these dimensions and juxtapositions should be such that, after the supplement is inserted in its cover pocket 6, the supplement, when the cover arm 9 is folded, rests entirely within the confines of the rear cover 2, and the supplement leaves 7, when the cover arm 9 is unfolded, will be projected to a position where their orbit clears the orbit of the leaves 4 of the permanent volume.

The permanent volume and its companion supplement are made ready for joint use by opening the rear cover 2 and unfolding the cover arm 9 of the supplement, as shown in Fig. 4. The supplement leaves 7 will be projected outside the rear cover 2 to a position where their orbit will clear the orbit of the leaves 4 of the permanent volume. Thus, each set of leaves can be freely turned without interfering with the position of the other set and, of course, both sets can remain fully open concurrently at the desired pages. When the permanent volume and supplement are not in use, the cover arm 9 is folded back so as to rest within the confines of the rear cover 2 and the permanent volume is then closed in the usual manner. The closure can be made without straining the binding of the permanent volume, since its back 3 is wider than the thickness of its leaves 4. The supplement thus fits within and forms a component part of the permanent volume, and yet may be readily removed therefrom and replaced when desired.

It will be noted that the permanent volume herein described accommodates its companion supplement in a pocket 6 inside its rear cover 2, which pocket 6 opens vertically adjacent the back 3. This is the type of pocket used in conventional pocket supplement books and was selected for particular description and illustration to demonstrate how readily my invention can be adapted to existing pocket supplement books. However, the objects of my invention can be fulfilled whether the pocket is located in the front

or rear cover of the book; whether the pocket opens vertically, adjacent one side of a cover or the other; or whether it opens horizontally, adjacent the top or bottom of the cover. A change 5 in the location of the pocket merely requires a change in the shape and folds of the coupling member of the supplement.

Furthermore, although the removable supplement described herein makes particular reference 10 to the type which connects to its companion permanent volume by insertion into a cover pocket of the latter, it is understood that I have particularized this form of attachment by way of example only and that numerous changes in the method of connection and other details of construction may be resorted to without departing from the spirit and scope of the invention as hereinafter claimed.

Having thus described my invention, I claim:

1. A book having inside the rear cover a pocket 20 opening sideways adjacent the back in combination with a supplement consisting of an oblong trunk, two arms projecting therefrom, and a plurality of attached leaves, the trunk being narrower than the book cover, the first arm being shaped to fit the cover pocket and projecting from the left side of the trunk, the upper horizontal border of said arm being a continuation of the upper horizontal border of the trunk, said arm being folded backward along its line of junction with the trunk and inserted in the cover pocket, the second arm being smaller in length and width than the book cover and projecting from the top of the trunk, said second arm being scored along its line of junction with the trunk, the plurality of leaves being smaller in length and width than the said second arm and mounted within its confines.

2. A pocket supplement consisting of an oblong 25 trunk, two arms projecting therefrom, and a plurality of attached leaves, the first arm projecting from a vertical border of the trunk, a horizontal border of said arm being a continuation of the same relative horizontal border of the trunk, said arm being folded backwards along its line 30 of junction with the trunk, the second arm projecting from the aforementioned horizontal border of the trunk, said arm being scored along its line of junction with the trunk, the plurality of leaves being smaller in length and width than the said second arm and mounted within its confines.

3. A pocket supplement consisting of a trunk, an arm projecting from a horizontal border of the trunk, a second arm projecting from a vertical border of the trunk, and a plurality of leaves mounted on the second arm.

4. A pocket supplement cover consisting of a 35 trunk and two arms completely and permanently united to the trunk, one arm projecting from a horizontal border of the trunk, the other arm projecting from a vertical border of the trunk.

MILTON H. HARRIS.
